UNITED STATES PATENT OFFICE

2,566,128

TRASH CONTAINER

Maurice Henkin, Memphis, Tenn., assignor, by
mesne assignments, to Metalcraft Manufacturing
Corp., Memphis, Tenn., a corporation of
Tennessee

Application April 2, 1948, Serial No. 18,630

1 Claim. (Cl. 220—36)

1

This invention relates to trash containers, and particularly relates to trash containers having lids or closures hinged to the body portion which include means for effecting opening and closing of the lid.

It further relates to new improvements in the hinge for such lids.

The principal object of the invention is to provide a mechanically simple lidded container.

A further object of the invention is to provide a new and improved means for opening and closing the lid of the container.

A further object of the invention is to provide a new and improved hinge for the lid of such a container.

A further object of the invention is to combine with such a hinge a new handle arrangement.

And a further object of the invention is to generally improve the design, and efficiency of construction of lidded trash containers.

The means by which the foregoing and other objects of this invention are accomplished and the manner of their accomplishment will readily be understood from the following specification upon reference to the accompanying drawings, in which:

Fig. 1 is an elevational view of the back of the container showing the lid in closed position and the arrangement of the lid-opening means.

Fig. 2 is a sectional elevation on the line II—II of Fig. 1.

Fig. 3 is a top plan view of the container with a portion of the lid broken away to illustrate the arrangement of the hinge means.

Fig. 4 is a fragmentary front view on an enlarged scale of the lower portion of the container illustrating the positioning of the pedal of the closure operating means.

Fig. 5 is a fragmentary rear view illustrating the positioning of parts of the closure operating means when the lid is in open position.

Fig. 6 is a fragmentary side elevational view illustrating the relation of the parts when the lid is in open position.

Referring now to the drawings in which the various parts are indicated by numerals:

The container of this invention comprises a body portion 11 which is preferably substantially rectangular in cross section and includes front wall 11A, rear wall 11B and side walls 11C which are preferably formed from a single integral, continuous sheet-like member, the corners between the respective wall portions being preferably rounded. Closure of the bottom of the container is effected by a bottom 11D which is

2

secured and sealed along its edges to the respective lower edges of the vertical walls. The respective upper edges of the vertical walls of the container are preferably formed into a rolled bead 13 which extends without interruption along the entire upper edge of the body portion. Preferably this bead encloses a stiffener wire 15.

The body portion is preferably provided with front and rear supports 17, 19 which are preferably elongated members extending along at least a major portion of each of the front and rear edges of the bottom of the container. Closure of the container is effected by a lid 21 which is hinged to the body portion in the manner hereinafter described.

Preferably the lid 21 is, as illustrated in Figs. 1, 2 and 6, upwardly arched and is preferably provided with a peripheral gasket 23 which is provided to seat upon the bead 13 in effecting closure of the container. The rear wall 11B of the container adjacent the bead 13 is provided with a pair of spaced slots 25, the upper edges of the slots being preferably contiguous to the bead, so that the bead bridges the slots.

The slots 25 are preferably spaced substantially equidistant from the vertical center line of the rear wall 11B and are provided to permit the passage therethrough of hinge members 27, 28, below bead 13, by which hinge members the lid 21 is hingedly secured to the container. The hinge members are substantially identical and each include a forward portion which is rigidly secured to the inner side of the lid 21 and project rearwardly therefrom, being centrally downwardly deformed to pass around and embrace the bead 13 as the members are passed through the slots 25 below the bead.

As illustrated in Figs. 2 and 6, the central section 29 of each of the hinge members is deformed into substantially U-shape to embrace the segment of the bead so that the bead is enabled to serve as a hinge pin for the hinge members 27, 28.

Rearwardly of the central section, each of the hinge members includes a rearwardly projecting portion 31 and each is continued from the rear end of the rearwardly projecting portion with an upwardly projecting portion 33. Extending between the upper ends of the upwardly projecting portions 33 as a handle member 35, which, it will be seen, is normally positioned above and rearwardly of the hinge center. As shown, the handle member 35 is a separate member secured to the portions 33. It may, however, be formed integral therewith as in a cast unit.

One of the hinge members, in the present instance, the member 28, is provided with an apertured ear 37 which is rigidly secured to the hinge member adjacent the junction of the rearwardly projecting portion 31 with the upwardly projecting portion 33 of the member 28. Pivotally secured to the ear 37, as by hook 39, is an elongated reach rod 41 which extends downwardly from the point of connection at a slight angle of inclination from the vertical and is preferably provided at its lower end with a second hook 43. Through the medium of the hook 43 the reach rod is coupled to a lever arm 45 of a rocking shaft 47. The rocking shaft 47 extends from rear to front of the container substantially along the midline thereof and is journalled adjacent its opposite ends in the support members 17, 19. Forwardly of the front support 17 the rocking shaft is provided with a pedal 49 for rotating the shaft to effect operation of the lever arm and reach rod for movement of the lid.

It will be seen that the lever arm 45 is disposed at an angle of inclination from the vertical of the nature of forty-five degrees and that the respective lengths of the reach rod 41 and the lever arm 45 are such that the sum of their lengths is substantially in excess of the distance between the ear 37 and the shaft journal formed in the rear support 19. Preferably the lever arm, rocking shaft and pedal are formed of an integral rod-like member.

The pedal 49 is provided with projecting extremities 49A, 49B, which are disposed in planes intersecting at an obtuse angle with one of the extremities 49A being preferably positioned substantially parallel to the lever arm 45.

When the container has been assembled in the manner described, operation of the lid to effect opening and closing thereof may be accomplished through the medium of foot pedal 49. Thus as the extremity 49A is depressed the shaft 47 is rotated, depressing the lever arm 45, correspondingly lowering the reach rod 41 and moving the rearwardly projecting ear 37 about the hinge center formed by the bead 13 so as to lower the rearwardly projecting portion 31 and to raise the lid 21.

It will be seen that, as the lid 21 is upwardly arched, when it has been moved to the open position illustrated in Fig. 6, the mass of weight of the lid is rearward of the hinge center so as to tend to maintain the lid in upright position, further rearward movement of the hinge being prevented by the engagement of the rearwardly projecting portions 31 against the rear wall 11B. This counter-balancing of the lid by virtue of its arch is assisted by the handle portion 35 of the hinge means, which, being disposed upwardly and rearwardly of the hinge center in normal closed position of the lid, is, therefore, eccentric of the hinge center and tends to exert a counter-balancing force being downwardly urged by gravity.

It will thus be seen that if desired the weight of the handle may be increased so that the handle may assume all of the requisite counter-balance function for maintaining the lid in open position upon operation of the foot pedal 49. Depression of pedal extremity 49A to effect opening of the lid effects equal raising of the opposite extremity 49B, and when it is desired to re-effect closure of the lid the extremity 49B may be depressed, thus effecting counter-rotation of the shaft 47 and reversal of the movement of the lever arm

and reach rod so as to effect repositioning of the parts in normal closed position.

It will further be noted that when the container is closed the handle portion 35 is conveniently positioned for manual transportation of the container, as for example, when it is desired to discharge the contents therefrom. As such containers are frequently employed for the reception of trash or garbage, undesired spillage of which is to be avoided, the positioning of the handle 35 above and rearwardly of the hinge center enables the user to raise the entire container by the handle, thus exerting a downward force on the lid, maintaining it in closed position until intentional discharge of the contents may be effected, and this downward closing force is further assisted by the weight of the contents of the container so that the container is satisfactorily retained in closed condition during movement of the container through the use of the handle 35.

It will be understood that the coupling of the reach rod and lever arm may be effected with the hinge member 27, the positioning of the lever arm and of the pedal 49 being reversed thereby without departing herefrom.

It will also be understood that while it is preferable to employ an upwardly arched lid, as the lid 21, the arch may be modified or eliminated entirely if desired without departing herefrom.

It will also be understood that the reach rod may be coupled to the hinge means in other manner than through the ear 37.

I claim:

55 A container, a lid for effecting closure of said container, a pair of spaced hinge members attached to said lid and connected hingedly to said container, a pair of substantially L-shaped members respectively integral with said hinge members and positioned exterior said container with one leg of each L member in substantially horizontal alignment with said hinge means and the other legs of said L members respectively extending upwardly from their junctions with the first mentioned legs and diverging away from said container, an eye secured to and projecting from one of said upwardly turned legs adjacent the junction of said one leg with its related horizontal leg, a handle member secured to and spanning between the upper ends of the last mentioned legs and being spaced above said horizontal legs and rearward of said container, and operating means for effecting opening and closing movement of said lid including a reach rod coupled to said eye.

MAURICE HENKIN.
